SOFT DRINK DISPENSER

Hans W. Bruntjen, Hopkins, Minn.

Application September 10, 1958, Serial No. 52,585

Term of patent 14 years

(Cl. D2—3)

FIG. 1

FIG. 2

FIG. 3

FIG. 4

Fig. 1 is a view in perspective of my soft drink dispenser, showing my new design;

Fig. 2 is a view in top plan;

Fig. 3 is a view in side elevation; and

Fig. 4 is a view in rear elevation.

The side of the dispenser not shown in the drawings is like the side shown.

I claim:

The ornamental design for a soft drink dispenser, as shown and described.
